UNITED STATES PATENT OFFICE.

JOHN EDWARD WYANT AND ELI MARTIN WYANT, OF WATERLOO, IOWA.

CURTAIN-FIXTURE.

SPECIFICATION forming part of Letters Patent No. 335,789, dated February 9, 1886.

Application filed April 7, 1885. Serial No. 161,432. (No model.)

To all whom it may concern:

Be it known that we, JOHN EDWARD WYANT and ELI MARTIN WYANT, citizens of the United States, residing at Waterloo, in the county of Black Hawk and State of Iowa, have invented a new and useful Curtain-Fixture, of which the following is a full, clear, and exact description, reference being had to the accompanying drawings, forming part of this specification, in which—

Figure 1 represents a perspective view of a curtain-roller with our improvement attached. Fig. 2 represents a perspective view of the slotted tube removed.

Our invention relates to curtain-fixtures; and it consists in one or more slotted tubes or clamping-plates, forming a continuous support, and adapted to be slipped upon the end of roller and to secure the curtain to the roll without the aid of tacks, nails, or other fastening devices, as we will hereinafter fully describe and claim.

To enable others skilled in the art to make and use our invention, we will now proceed to describe the exact manner in which we have carried it out.

In the said drawings, A represents a curtain-roll of ordinary construction, and which may be of any desired length.

B represents the curtain, and C represents our improved slotted tubes or clamping-plates, which are composed of metal, and secured to the roll by being slipped over the end of the same, thereby forming a continuous support for the curtain. It will be seen by reference to Fig. 2 that these tubes conform very nearly to the circumference of the roll, and the open sides of the tubes extend a little beyond the center of the roll, so as to give greater pressure; also to adapt themselves to rolls of different diameters.

If necessary, the tubes C may be japanned or otherwise plated, to prevent their discol-

ing or injuring the curtain, and they may be made of any desired length and material. 45

When it is desired to attach the curtain to the roll, it is only necessary to lay the edge of the same upon the roller, and then press one or more of these slotted tubes upon it until the tubes extend continuously the whole length of the roll, when, by reason of the elastic nature of the tubes, the curtain is firmly bound upon the roll at every point throughout its length, thereby dispensing with the use of tacks or similar fastening devices. It is also manifest 55 that when it is desired to remove the curtain it is only necessary to remove the tubes, the material composing the curtain, even though of finest nature, not being injured by reason of its contact with the tubes or roll. 60

We are aware that metallic clips have been used instead of tacks for securing curtains to their rods; but by the use of such clips loose spaces are left, which allow the curtain to sag at the points between the clips. 65

We are also aware that cylinders, in each of which was formed a slot, have been slipped on the roller from each end over the curtain, and this construction we therefore do not claim as our invention. 70

Having thus fully described our invention, what we claim as new, and desire to secure by Letters Patent, is—

The means described for securing curtains to rolls, which consists of metallic slotted tubes 75 extending continuously the whole length of the rod, and adapted to engage the roll and secure the curtain independent of other fastening devices, substantially as herein described.

JOHN EDWARD WYANT.
ELI MARTIN WYANT.
